UNITED STATES PATENT OFFICE.

HARRY C. ARNOLD, OF BROOKLINE, MASSACHUSETTS, ASSIGNOR TO CONVERSE RUBBER SHOE COMPANY, OF MALDEN, MASSACHUSETTS, A CORPORATION OF MASSACHUSETTS.

DESIGN FOR A TIRE.

53,108.

Specification for Design.

Patented Mar. 25, 1919.

Application filed March 28, 1917. Serial No. 158,129. Term of patent 14 years.

To all whom it may concern:

Be it known that I, HARRY C. ARNOLD, a citizen of the United States, residing at Brookline, in the county of Norfolk and State of Massachusetts, have invented a new, original, and ornamental Design for Tires, of which the following description, in connection with the accompanying drawings, is a specification, like characters on the drawings representing like parts.

Referring to the drawing:

Figure 1 is a perspective view of a vehicle tire showing my new design; and

Fig. 2 is a developed plan view of a portion thereof.

I claim:

The design for a tire, as shown.

In testimony whereof, I have signed my name to this specification.

HARRY C. ARNOLD.
